United States Patent Office.

ALFRED McDANIEL, OF DUBUQUE, IOWA.

Letters Patent No. 88,193, dated March 23, 1869.

WASH-BOILER.

The Schedule referred to in these Letters Patent and making part of the same.

To all whom it may concern:

Be it known that I, ALFRED McDANIEL, of the city and county of Dubuque, and State of Iowa, have invented a new and useful Improvement in Wash-Boilers; and I do hereby declare the following to be a full, clear, and exact description of the nature thereof, sufficient to enable others skilled in the art to which my invention appertains, to fully understand and use the same, reference being had to the accompanying drawings, making part of this specification, in which—

Figure 1 is a central longitudinal section of the device illustrating my invention.

Figure 2 is a central horizontal section, in the line z , fig. 1.

Figure 3 is a top view of the internal boiler.

Similar letters of reference indicate corresponding parts in the several figures.

This invention relates to that class of wash-boilers in which there is a circulation of the hot water; and

It consists in placing projecting strips at the side of an internal boiler, and a ledge of the top thereof, whereby the flow of the water is equable, and its overflow is prevented, as will be hereafter described.

In the drawings—

A represents an ordinary wash-boiler, within which is placed the additional boiler B, which is constructed of suitable form and size to fit said outer boiler, but to leave a space between them.

C is a conical, or funnel-shaped bottom, which may have a series of openings, or apertures, and rests on the bottom of the outer cylinder, as seen in fig. 1.

A series of bars D, is placed within the boiler B, and affords lodgment, or rest for the cloth to be washed, as ordinarily.

To the outer side of the boiler B, I secure a series of strips, E, which project at an angle therefrom, and extend vertically from the top to a point below the centre of the boiler.

These strips are arranged side by side, and when the boiler is in its place, their outer edges come in contact with the inner face of the boiler B, as seen in fig. 2.

It will be seen that a series of channels, b, is formed, through and in which the water ascends, and this ascent is thereby uniform.

F is a ledge, mounted on or secured to the top of the boiler, or the strips E. This ledge extends around the top of the boiler, and, by preference, in an inclined direction, as seen in fig. 1.

A space is left between the boiler and the ledge, so that as the water ascends in the channels b, and reaches the ledge, it is caused to strike it, and be thereby deflected so as to fall into the boiler, and then circulate as formerly.

The overflow of water is thus prevented, which overflow is a serious objection to boilers, and liable to extinguish the fire.

In the operation of the boiler, the water first ascends outside of the funnel C, then through the passages b, striking the ledge F, down into the boiler, through the clothes, and then out of the boiler, through its bottom, or spaces a.

The strips E, likewise, assist in holding and supporting the inner boiler.

Having thus described my invention,

What I claim as new, and desire to secure by Letters Patent, is—

The series of projecting strips E, between the inner and outer boilers, forming passages b, and the ledge F, in combination with the internal and external boiler, as and for the purpose described.

ALFRED McDANIEL.
